UNITED STATES PATENT OFFICE.

HENRY A. WISE WOOD, OF NEW YORK, N. Y., ASSIGNOR TO THE CAMPBELL PRINTING PRESS AND MANUFACTURING COMPANY, OF SAME PLACE.

PRINTING-PRESS.

SPECIFICATION forming part of Letters Patent No. 618,490, dated January 31, 1899.

Application filed December 19, 1892. Serial No. 455,614. (No model.)

To all whom it may concern:

Be it known that I, HENRY A. WISE WOOD, a citizen of the United States, residing at New York, in the county of New York and State of New York, have invented a new and useful Improvement in Printing-Presses, of which the following is a specification.

The aim of this invention is to provide a new manipulating mechanism for controlling a web of paper or its equivalent. I have shown the invention as applied as the web-manipulating device for a reciprocating-cylinder web-printing press, and in this application I have further claimed certain improvements in this style of printing-machine.

Figure 1 is a side elevation of a printing-press embodying my improvements. Fig. 2 is a plan of the same. Fig. 3 is a sectional elevation illustrating the path of the web. Figs. 4, 5, and 6 are similar diagrams illustrating the operation of the parts; and Figs. 7 and 8 are views similar to Figs. 4 and 6, illustrating a modification of the feeding apparatus.

The principal part of this invention relates to an improved manipulating mechanism for handling a web of paper or its equivalent. This manipulating mechanism is especially applicable to any form of machine in which a web or its equivalent is to have an intermittent movement in a part of the mechanism. I have shown the same as applied to a traveling-cylinder web-press in this case, to which the same is especially adapted; but it is to be understood, of course, that the improved manipulating device can be applied to any mechanism in which the same is found useful without departing from the scope of my invention as expressed in the claims.

My invention further consists of certain forms of brake for a web especially adapted for use in connection with my peculiar manipulating mechanism.

My invention further consists of details, arrangements, and combinations hereinafter pointed out; and specifically set forth in the appended claims.

Referring now to the drawings and in detail, 10 and 11 represent the side frames of a printing-press. Between these side frames

are secured in any suitable manner form-beds A and B, upon which the usual printing-forms or type may be placed to make the impression. These form-beds, as shown, are arranged in different horizontal planes and 55 are parallel, but are not placed in the same vertical plane, or, in other words, one bed is arranged horizontally in advance of the other. This arrangement of beds in a traveling-cylinder printing-press is not specifically claimed 60 in this case, as the same is claimed in my companion application for patent filed January 3, 1898, Serial No. 665,358.

Coacting with the bed A is the reciprocating impression-cylinder C, and coacting with 65 the bed B is the reciprocating cylinder D, which cylinders are both mounted in a suitable carriage, as hereinafter described.

E represents the roll of paper, which may be mounted in any convenient manner in the 70 press-frame or otherwise and from which the web is led.

F F denote the form-inking rollers, which are mounted so as to reciprocate with each impression-cylinder, on each side thereof, and 75 which are adapted to ink the forms in the usual well-known manner. Any of the usual means may be used for supplying ink to these form-inking rollers, and it is not thought necessary to show this inking apparatus in 80 this case, as the same is well understood.

G represents the peculiar feeding device or rotary looper hereinafter referred to, and H represents what I call the "long point" of the same.

Referring to Fig. 3, which is a sectional elevation with the parts in the position shown in Fig. 1, the path of the web will first be described. From the paper-roll E the web is led into the bite of the rollers 26, 25, and 24, 90 which are continuously driven by gearing, as hereinafter described, to unwind the web from the web-roll E. From the roll 24 the web passes down underneath the rotary looper G and up over the roller 23 and forms a loop 95 around the rotary looper G between the rollers 24 and 23. From the roller 23 the web passes to a guide or roller 22, moving with the impression-cylinder D, down under the impression-cylinder D, and up over the roller 21, also moy- 100

- ing with the impression-cylinder D. From the roller or guide 21 the web is led up under the guide-roller 20 and then up over the guide-roller 19. The guide-roller 19, if desired, may be adjustable for the purpose of obtaining register of the web between the two impression-cylinders. From the roller or guide 19 the web passes to the roller or guide 18, moving with the impression-cylinder C, then under the impression-cylinder C, and up over the guide or roller 17, also moving with the impression-cylinder C, to the stationary guide or roller 16. From the guide or roller 16 the web passes down under the roller or guide 15, up over the rotary looper G, and then down into the bite of the delivery-rollers 14, 13, and 12, which may be continuously driven, as by gearing hereinafter described, to continuously deliver the web from the press. It will be seen that the web between the rollers or guides 15 and 14 forms a loop around the rotary looper G. The rollers 23 and 15 may have brakes, as 28 and 27, coacting therewith, and these brakes are so arranged as to nip the web during the act of printing, whereby the pull of the cylinders during the printing operation will not affect the amount of web between the rollers 15 and 23 and the web-manipulating mechanism will not affect the web in the press. When the cylinders are not in impression, these brakes are released and the web can be pulled forward around the impression-cylinders D and C. All these parts, before described, are so arranged that a sheet will be printed for each movement of the impression-cylinders in either direction, or two sheets will be printed for each complete forward-and-backward movement of the impression-cylinders.
- It is evident, of course, that the web could be led in the opposite direction through the press—that is, in through the rollers 12, 13, and 14 and out through the rollers 24, 25, and 26—and if this were the case all the necessary change that would have to be made would be to throw the long point of the rotary looper G around one hundred and eighty degrees and to gear the feeding-in and out rollers to turn oppositely from the way shown, so that the loops would be properly formed to act in connection with the properly-moving feeding-in and feeding-out rollers, and in this case the impression-cylinder D would be the second impression-cylinder and would have to carry the offset mechanism, herein-after described.
- I have described my press as a perfecting-press, although, of course, it is evident that many of my improvements could be applied to a single-cylinder machine, in which the web was only printed upon one side, and in that case it might be considered that the upper bed and cylinder were omitted.
- The action of the rotary looper G will be herein-after described.
- The rotary looper G is mounted upon a shaft 29, which is turned twice for each com-

plete forward-and-backward movement of the impression-cylinders.

To prevent offset from the first printed side of the web upon the second impression-cylinder C, I mount a fountain in the reciprocating carriage, which carriage carries the impression-cylinders, and so arrange the same that the fountain will deposit a thin coating or film upon the surface of the second impression-cylinder, whereby offset will be prevented. This fountain may be organized as follows: A plush roller 31 is arranged to bear against the surface of the second impression-cylinder C, and bearing against this plush roller is a metal distributor 32, which bears against the fountain-roller 33, which is arranged in the fountain 34. This fountain-roller 33 is arranged so as to nearly cover the entire top of the fountain 34, whereby the liquid will be prevented from splashing as the impression-cylinders reciprocate. The impression-cylinders C and D have on the ends or the shafts thereof the usual gears 35, which mesh with stationary racks 36, secured to the sides of the form-beds, as shown in Fig. 2, whereby as the impression-cylinders are reciprocated they will oscillate and always keep in register with the form-beds. From the gear 35 of the impression-cylinder C a gear 37, mounted on the shaft of the plush roller 31, is driven, and this gearing is preferably so proportioned that the plush roller 31 and the impression-cylinder C will have the same peripheral speed. On the outside end of the shaft of the plush roller 31 is arranged a small pinion 38, which meshes with and drives a large gear 39, fastened on the outside end of the roller 32, and this gearing is proportioned, as shown, so that the distributor 32 will turn at a much slower peripheral speed than the plush roller 31, whereby there will be considerable slip between the plush roller and the distributor. If desired, the fountain-roller 33 may be geared to turn with the distributor 32 at the same peripheral speed, although this is not always necessary, as the fountain-roller 33 may be turned simply by contact with the distributor 32. As the gearing on the side of the cylinder oscillates of course this distributing mechanism will be properly turned to deposit a thin coating or film on the impression-cylinder C. This offset-preventing device works substantially on the same principle as that shown, described, and claimed in patent to John H. Stonemetz, granted February 1, 1898, No. 598,122, and the slip between the plush roller and the distributor serves to deposit only a very thin coating or film upon the impression-cylinder.

The impression-cylinder C is mounted in brackets or blocks 40, which may be tied together, if desired, to form a strong framing, and the impression-cylinder D is arranged in similar brackets 41. These brackets 40 and 41, are bolted or secured to sliding frames or carriages 42, which are gibbed to the guides

43, formed or fastened on the side frames, as shown. These carriages 42 have teeth 44 on the underside of the same, as shown, whereby the same can be reciprocated, as hereinafter described.

The driving mechanism may be organized as follows: A short or stub shaft 45 is journaled in the main frame 10, and the same may have the usual loose and tight pulleys 46 and 47, by which power can be imparted to operate the machine. On this shaft 45 is arranged a pinion 48, which meshes with and drives the large intermediate 49, mounted on a stud 50, secured to the main frame 10, as shown. This intermediate 49 drives a gear 51, which is secured upon the end of shaft 52, journaled in the main frame 10, and also on this shaft 52 is arranged a gear 520, which meshes with gears secured upon the ends of the continually-running rollers 12 14 and 26 24, as shown. The rollers 12, 13, and 14 and the rollers 24, 25, and 26 are geared together, as shown, whereby they will be turned in unison and will act to continuously pay the web out of and into the press. From the driving-pinion 48, by means of the intermediate 500, the gear 53 is driven, and this gear 53 is fastened upon the end of the shaft 29, which is the shaft of the rotary looper G. The gear 53 also meshes with and drives a large intermediate 54, fastened on a stud or shaft 55, secured in the main frame, as shown, and this intermediate 54 meshes with and drives a large gear 56, mounted upon a shaft or stud 57, which is fastened to the frame 10, as shown. This gear 56 carries a crank-pin 58, on which is arranged a block 59, and this block 59 engages a slot 62 of the vertical portion 61 of the yoke 60, which yoke 60 is mounted so as to be capable of a reciprocating horizontal movement in the brackets 63 and 64, secured to the main framing, as shown. Thus as the gear 56 revolves the yoke will be given a forward-and-backward reciprocation, which movement will be very smooth and powerful and will gradually reverse the parts evenly in both ways, as no pitmen are used. The yoke 60 has teeth 65 formed thereon, which engage the gear 66, fastened on the shaft 67, and, if desired, this shaft 67 may be carried across the press and journaled in the main frames 10 and 11. Fastened on this shaft 67 are two sectors 68, which mesh with teeth 44 of the carriages 42, before referred to, whereby as the yoke 60 is reciprocated the reciprocating motion will be multiplied and imparted to the carriages 42. This geared-up yoke may be arranged in any desired manner and constitutes an efficient means for reciprocating either the single cylinder of a single machine or the double cylinders of a double-cylinder machine. The gear 56 is so arranged as to make half as many revolutions as the gear 53, and this is done in the present instance by making the gear 56 of double the size of the gear 53, whereby the rotary looper may act both to feed the web in and out of

the press when the cylinders are off impression in either direction. A roll 69 may be arranged beneath the yoke 60 at the point at 70 which the teeth of the same engage the gear 66, and this roll may be mounted on a stud 70. This roll will act to keep the teeth before referred to nicely in mesh.

The brakes 27 and 28, before referred to, 75 may be properly operated by the following means: A cam 72 may be arranged upon the shaft 29, and bearing against the face of this cam is arranged a roller 73, which roller 73 is journaled in the end of a sliding arm 74. 80 This arm 74 carries a block 75, and the roller is constantly pressed against the face of the cam by means of the spring 76, which bears against the block 75 and at a fixed point or bracket 77. The rod 74 is mounted in suitable bearings, as shown, so as to be capable of a horizontal movement. The brake 27 is fastened on a shaft 78, and the brake 28 is arranged on a similar shaft 80. On the ends of these shafts are arranged the arms 79 and 81, 90 as shown, and these arms connect by links 82 and 83 to the block 75, as shown. Thus when the parts are in the position shown in Fig. 1 the spring 76 will press the block 75 to the left, and thus will cause the brakes to 95 tightly engage the rollers 15 and 23 with a yielding pressure. The cam 72 in the present design of the press is so arranged as to move the block 75 slightly to the right from the position shown in Fig. 1, and thereby release 100 or open the brakes. These parts are so proportioned that the web will be tightly held by the brakes during the printing operation between the rollers 23 and 15, which rollers are the points limiting the stationary part of 105 the web, and the brakes will be released when the cylinders are reversing off the form-beds in either direction, whereby the web can be pulled forward around the impression-cylinders and be fed during the reversal of the cylinders. This braking mechanism forms an important device which can be applied to any reciprocating-cylinder printing-press and is specially applicable to a reciprocating-cylinder printing-press in which the impression cylinder or cylinders print in both ways, as the strain in printing in both ways on the web comes in both directions, and by use of the double brake a loop of the web, so to speak, as the web between the rollers 23 and 115 15, will be held stationary and taut during the printing operation.

The rollers 16 and 19, before referred to, are mounted in suitable brackets 800 and 810, secured to the main frames, as shown.

I will now describe the action of the feeding mechanism.

The entire feeding of the web around the impression-cylinders is preferably accomplished by a single piece, which I term a "rotary looper," acting in conjunction with the continuously-running feeding-in and feeding-out rollers. This rotary looper G is made cam-shaped and acts to take up and pay out

the loops of the web between the rollers 24 and 23 and between the rollers 15 and 14, so that the web will be pulled around the impression-cylinders as they are reversing and so that the web in the press will be held stationary during the printing operation. The rotary looper is preferably completely rotated and so arranged that the entire periphery of the same will contact with the web, whereby the rotary looper will constantly control the amount of web in the loop. This rotary looper G may be made of a cam-shaped drum or of any desired construction, and one way is to make the same of light cam-shaped pulleys, as 30, and to key them upon the shaft 29, and these pulleys may be set as closely together as desired, so as to form substantially a cam-shaped drum. These pulleys 30 are counterbalanced by means of lead or a solid hub, as 90, cast therewith, and by means of this counterbalancing the center of gravity of said rotary looper G will be arranged to coincide with the axis of the shaft 29, whereby the rotary looper can revolve very smoothly and at a high speed without vibration or jar.

In Figs. 1 and 3 the impression-cylinders are shown as in impression and as moving to the left; but now to follow the action of the rotary looper reference should be had to Figs. 4, 5, and 6. In Fig. 4 the impression-cylinders are shown as just clearing the forms on their movement to the left and as commencing their reversing movement at their left-hand extreme. In Fig. 5 the cylinders are shown at their left-hand extreme, and in Fig. 6 the cylinders are shown as just engaging the forms on their movement to the right and as having completed their left-hand reversing movement. Suppose now that the impression-cylinders are so timed and designed that they will be upon and off the forms an equal time—that is, supposing forty-five-degree lines to be drawn through the center of the shaft 57. Then the portion of the revolution of the crank-pin 58 included in the upper space will represent the movement of the impression-cylinders when they are on the forms and moving toward the right, and the lower space will represent their printing movement to the left. The right and left hand spaces will represent their reversals. In other words, the crank-pin must revolve through ninety degrees, or a quarter-turn, to take an impression and the same distance to reverse the cylinders. This proportion or design is not always followed, but is a convenient arrangement. Between Figs. 4 and 6, therefore, the crank-pin will have made ninety-degree movement in the right-hand space, into which the crank-pin movement is supposed to be divided, or the crank-pin will have turned ninety degrees, or a quarter-turn. As the shaft 29 is geared to turn twice as fast as the crank-pin, the rotary looper G will have turned one hundred and eighty degrees during this quarter-turn of the crank-pin. Supposing now that the length of the sheet which

it is desired to print, including the margins, &c., is twenty-four inches, then the continually-running feeding-in and feeding-out rollers will be so speeded that during each movement of the impression-cylinders they will pay in and out twenty-four inches of web, or during each complete forward-and-backward movement of the impression-cylinders 75 they will pay in and out forty-eight inches of web, or the length of two sheets. Starting now with the parts as shown in Fig. 4, where the impression-cylinders have just finished their printing movement to the left and are 80 starting on their reversing movement, and suppose the impression-cylinders to be moved to their left-hand extreme, as shown in Fig. 5, and then back to just engage the forms, as in Fig. 6, or to make a reversal occupying a 85 quarter-turn of the crank-pin 56, during this time, as before stated, the rotary looper G will make a half-turn and the loop in that portion of the web that is between the rollers 24 and 23 will be relieved, while at the same 90 time the loop will be taken up in that portion of the web between the rollers 15 and 14. During this quarter-turn of the crank-pin 56 the continuously-running feeding-in rollers and feeding-out rollers will have paid in and 95 paid out twelve inches of web; but as it is desired to shift twenty-four inches of web, or the length of a sheet, around the impression-cylinders the rotary looper G must take twelve inches of web from the lower loop and 100 draw the same amount through the press up into the upper loop, which twelve inches of web, added to the twelve inches of web fed in and out by the feeding-in and feeding-out rollers, will make a total shift of twenty-four 105 inches of web. Now as the impression-cylinders move to the right over the form-beds the rollers 12, 13, and 14 will act to pay twelve 110 inches of web out of the press and the rollers 24, 25, and 26 will act to pay twelve 115 inches of web into the press; but during the time that the cylinders are in impression and moving to the right the rotary looper G will turn from the position shown in Fig. 6 back to the position shown in Fig. 4, and the rotary looper G is so proportioned and designed 120 that it will evenly pay the loop of the web between the rollers 15 and 14 out to the delivering-rollers and will act to increase the web in the loop between the rollers 24 and 23 to 125 take up the web paid in by the feeding-in rollers. Thus in this last movement of the rotary looper the same will not act or have any tendency to disturb the web between the rollers 15 and 23. The brakes, acting in connection with these rollers, help the action of the rotary looper, as they will prevent any slight inequalities and imperfections in the cam-surface of the rotary looper from disturbing the stationary portion of the web. 130 The rotary looper G during the right-hand reversal of the impression-cylinders off the form-beds will turn again from the position shown in Fig. 4 to the position shown in Fig. 6, and

thus twenty-four inches of web will be shifted around the impression-cylinders when they are reversing in their right-hand extreme.

If the wrap of the web on the rotary looper 5 G should be neglected, the rotary looper would figure out to be what is known as a "heart-shaped" cam—that is, a cam in which the diameters are all equal, but in which the radii angularly constantly increase and decrease 10 for one hundred and eighty degrees; but in designing the cam account has to be taken of the wrap of the web, and the cam or rotary looper is so proportioned that the web during the printing action of the cylinders, as before 15 described, will be evenly taken up in the lower loop and will be evenly paid out in the upper loop. Thus this rotary looper G forms a very neat, simple, and efficient device for feeding the web into and out of the press.

20 Another great advantage that follows from the use of the rotary looper G is as follows: It will be seen by reference to the diagrammatic figures that the long point II of the rotary looper G always moves in the same direction as that in which the web is moving, or, in fact, it might be said that the whole surface of the rotary looper, where the same bears upon the web, moves in the same direction as that in which the web is moving. 25 It will further be seen that the surface of the rotary looper will move substantially at the same speed as the web moves in the loops. There may be a slip on the web due to the cam action, although this slip is very slight; 30 but as the looper moves in the same direction as the web it will comb or coax the web forward, whereby when the brakes are released and the looper comes into action the web will be very quickly started and very easily pulled 35 forward through the press. Therefore it is very advantageous in connection with this rotary looper to turn the same so that the same will rub or comb the web in a proper direction to feed the same through the press.

40 The rotary looper can be applied and used in connection with any device in which it is desired to intermittently move the web or its equivalent through a portion of a mechanism for any purpose. Tapes carrying sheets are 45 of course the equivalent of a web. Again, this rotary looper G could be used by running the same practically at half the speed at which the same now runs relatively to the impression-cylinders to feed the web forward 50 in a press in which the cylinders only print in one direction—such, for example, as is shown in Letters Patent to W. P. Kidder, No. 291,521, granted January 8, 1884. This rotary looper consists in its simplest form of 55 means, as guides, for leading the material to form a loop and a rotating member interposed in each loop.

In the figures previously described I have 60 shown the rotary looper or cam as accomplishing the double function both of feeding the web into and out of the press; but, if desired, this rotary cam could be used simply to

feed the web into the press or out of the press, or a different looper could be used to feed in and feed out, as shown in Figs. 7 and 8. In Fig. 7 the impression-cylinders C and D are shown as commencing their reversing movement at their left-hand extremes and in Fig. 8 are shown as having completed their reversing movement. In this case a rotary looper J, similar in construction to the rotary looper G, before described, and having a long point II', is interposed in the loop formed between the rollers 16 and 14, and another rotary looper K is interposed in the loop of the web between the rollers 24 and 23, and this rotary looper K has a long point or end II'. These rotary loopers are geared to turn in the same direction, and in Fig. 7 the long points of the same are shown as pointing down in the same direction, and in Fig. 8 they will also be pointing in the same direction, but upwardly instead of downwardly. This double rotary looper will act the same as the rotary looper G, except that the looper J will act to feed the web out, and the rotary looper K will act to feed the web into the press. There are many other ways in which this rotary looper could be proportioned and designed; and I do not at all wish to be limited to any specific construction herein shown and described so far as my broad invention is concerned. In this last modification the lower looper K could be omitted and dependence for the entire feed could be placed upon the upper looper J. With this arrangement the lower loop would be simply a loose loop in the web, from which the feed around the impression-cylinders would be pulled. In designing this cam-shaped looper of course the contour of the same would be varied if the proportion of the movement of the impression-cylinders during the printing movement relatively to the reversing movement should be varied.

In the offset-preventing device, as before described, any suitable fluid may be used, as oil, as is described in the Stonemetz application before referred to, or water could be used, and in this latter case the offset-preventing device would work upon the principle of that claimed in my patent granted July 15, 1890, No. 432,289.

The details and arrangements of the various parts that I have shown and described may be varied and differently arranged by a skilled mechanic without departing from the scope of my invention as expressed in the claims.

Having thus fully described my invention, what I claim, and desire to secure by Letters Patent, is—

1. In a web-manipulating mechanism, the combination of guides for supporting a web of paper, and a looping device of substantially the width of the web of paper arranged between said guides, and means for completely rotating said looper, whereby the looper will act to alternately take up and let out the web of paper, substantially as described.

2. The combination in a manipulating mechanism for the purposes set forth, of means for continuously feeding forward the material, guides for leading the material to form a loop, a looper interposed in this loop, and means for rotating the looper to control the amount of material in the loop, substantially as described. 70
3. The combination in a manipulating mechanism for the purposes described, of means for feeding the material forward, a looper around which the material is looped, and means for rotating this looper to control the amount of material in the loop, so arranged that the periphery thereof, will move in the same direction as the material, substantially as described. 75
4. The combination of means as guides or rollers for leading a web to form a loop, a member interposed in this loop, means for rotating the same, and means for continuously moving the web, arranged in the path of the web beyond the rotary member, substantially as described. 80
5. The combination of means as guides for leading a web to form a loop, a member interposed in the loop, means for rotating the member to control the amount of web in the loop, and so that the periphery of the same will move with the web, and means as continuously-running rollers arranged in the path of the web beyond the rotary member, substantially as described. 85
6. The combination with guides or rollers between which a web may be arranged to form two loops, of a rotary member adapted to control the amount of web in the two loops, substantially as described. 90
7. The combination with guides or rollers between which the web can be twice looped, of a rotary looper controlling the amount of web in the loops, and adapted to alternately take up and pay out the web in each loop, substantially as described. 95
8. The combination with means, as continuously-running rollers for feeding a web, of guides or rollers between which the web can be twice looped, and a rotary member adapted to control the amount of web in the two loops, substantially as described. 100
9. The web-looping device consisting of a cam-shaped rotary looper, guides or rollers arranged to loop the web around said rotary looper in opposite directions, and means for rotating said looper, whereby the web in the two loops will be alternately taken up and paid out, substantially as described. 110
10. The combination of a cam-shaped looper around which a web is led on opposite sides to form two different loops, guides or rollers for directing the web in this path, and means for continuously feeding the web forward and backward around this rotary looper, and means for revolving the rotary looper, substantially as described. 115
11. In a web-feeding device the rotary looper consisting of a cam-shaped revolving member, said member being counterbalanced so that its center of gravity will be in its axial center, substantially as described. 120
12. In a web-feeding device, the rotary looper consisting of a number of cam-shaped pulleys 30, arranged upon a shaft as 29, substantially as described. 125
13. In a web-feeding device, the rotary looper consisting of a number of cam-shaped pulleys as 30, arranged upon a shaft as 29, each of said pulleys being counterbalanced as at 90, substantially as described. 130
14. The combination in a web-printing press of the class described, of continuously-running rollers arranged to continuously feed the web from the press, and guides or rollers for leading the web to form a loop, and a constantly-rotating member interposed in this loop, substantially as described. 135
15. The combination in a web-printing press of the class described, of continuously-running rollers adapted to feed the web into, and continuously-running rollers adapted to feed the web out of the press, means as guides or rollers for leading the web to form loops before the same passes to the press and after the same passes from the press, and a rotary looper controlling the amount of web in these loops, substantially as described. 140
16. The combination in a web-printing press of a form-bed, a traveling impression-cylinder coacting therewith, guides adapted to direct the web around said impression-cylinder, means as guides or rollers for leading the web to form a loop, a rotary looper interposed in this loop, and means arranged in the path of the web beyond this looper for continuously delivering the web, substantially as described. 145
17. The combination in a web-printing press of a form-bed, a traveling impression-cylinder coacting therewith, guides for leading the web around the impression-cylinder, guides or rollers for leading the web to form loops before and after the same passes to the impression-cylinder, a rotary member controlling the amount of web in the loops, and means for feeding the web from the looper, substantially as described. 150
18. The combination in a web-printing press of a form-bed, a reciprocating impression-cylinder coacting therewith, guides or rollers adapted to direct the web around said impression-cylinder, guides or rollers between which the web can be looped both before and after it passes to the impression-cylinder, continuously-running rollers adapted to continuously feed the web into and out of the press, and a rotary looper controlling the amount of web in said loops, substantially as described. 155
19. The combination in a web-printing press of a form-bed, a reciprocating impression-cylinder coacting therewith, guides or rollers adapted to direct the web around the impression-cylinder, guides or rollers between which the web can be looped, a rotary looper

controlling the amount of web in this loop, said rotary looper being geared to turn twice for each forward-and-backward reciprocation of said impression-cylinder, and means for 5 delivering the web from the press substantially as described.

20. The combination in a web - printing press of a form-bed, a reciprocating impression - cylinder coacting therewith, continuously-running rollers adapted to feed the web into and out of the press, a rotary looper coacting with the rollers to form a web-manipulating mechanism, and gearing for rotating the looper twice for each complete forward-and-backward movement of the impression-cylinder, substantially as described.

21. The combination in a web-feeding device of two guides or rollers between which the web can be looped, a rotary looper controlling the amount of web between these rollers, and a brake acting in conjunction with the roller in the path of the web beyond the looper, substantially as described.

22. The combination in a web-feeding device of four rollers or guides between which the web can be twice looped a rotary looper controlling the amount of web in said loops, and brakes acting in conjunction with the rollers in the path of the web between the loops, substantially as described,

23. The combination in a web - printing press of a form-bed, a reciprocating impression - cylinder coacting therewith, a rotary looper for alternately drawing the web forward around the impression-cylinders, and a brake interposed between the impression-cylinder and the rotary looper, substantially as described.

24. The combination in a web - printing press of a form-bed, a reciprocating impression - cylinder coacting therewith, a rotary looper for alternately paying the web out, and drawing the same forward around the impression-cylinder, and brakes interposed in the path of the web between the rotary looper and the impression-cylinder, and the impression-cylinder and the rotary looper, substantially as described.

25. The combination in a web - printing press of a form-bed, a reciprocating impression-cylinder coacting therewith, a brake arranged in the path of the web before the same passes to the impression - cylinder, another brake arranged in the path of the web after the same passes from the impression-cylinder, a suitable web-feeding mechanism adapted to intermittently pull the web forward around the impression-cylinder, and a cam controlling both of these brakes so arranged that the brakes will not engage the web when it is desired to pull the web forward around the impression-cylinder, substantially as described.

26. The combination in a web - printing

press of two form-beds, a reciprocating impression - cylinder coacting with each form-bed, a suitable web-feeding mechanism adapted to intermittently pull the web forward around the impression-cylinders, a brake arranged in the path of the web before the same passes to the first impression-cylinder, a brake arranged in the path of the web after the same passes from the second impression-cylinder, and a cam controlling said brakes so arranged that the brakes will not engage the web when the web-feeding mechanism acts to pull the web forward around the impression-cylinder, substantially as described.

27. The combination in the web-feeding mechanism of a printing-press the class described, of continuously - running rollers adapted to continuously feed the web out of the press, a rotary looper bearing on a loop formed in the web before the same passes to said continuously-running delivery - rollers, and means for revolving said rotary looper, so that the surface of the looper will comb on the web in the direction that the web passes to said continuously-running rollers, substantially as described.

28. The combination in the web-feeding mechanism of a printing-press of the class described of continuously - running rollers adapted both to feed the web into, and out of the press a rotary looper interposed in two loops formed in the web before the same passes to, and after the same passes from the printing mechanism, and means for revolving said looper so that the surface of the same will tend to coax or comb the web in the direction that the same is moved by said continuously-running feeding-in and feeding-out rollers, substantially as described.

29. The combination in a web-perfecting reciprocating impression - cylinder printing-press of the second impression-cylinder having a gear 35 arranged to turn therewith, said gear 35 engaging the stationary rack 36, the fountain 34 moving with said second impression-cylinder, said fountain having a roller 33, a roller 31 engaging the periphery of the impression-cylinder C, a roller 32, arranged between the rollers 31 and 33, the gear 37 meshing with the gear 35, and arranged to turn the roller 31, and the gears 38 and 39 arranged to impart motion from the roller 31 to the roller 32, the whole so arranged that the roller 32 will bear upon the roller 31, but will turn at a slower peripheral speed than the roller 31, whereby there will be a slip between said rollers, substantially as described.

In testimony whereof I have hereunto set my hand in the presence of two subscribing witnesses.

II. A. WISE WOOD.

Witnesses:

JAMES J. MCGRATH,
WILLIAM E. FAY.
